UNITED STATES PATENT OFFICE.

FREDERICK C. SIMMONS, OF HIGHLAND PARK, PENNSYLVANIA, ASSIGNOR TO
PIONEER SUSPENDER COMPANY, A CORPORATION OF PENNSYLVANIA.

SUSPENDERS.

Application filed May 27, 1924. Serial No. 716,118.

To all whom it may concern:

Be it known that I, FREDERICK C. SIMMONS, a citizen of the United States, residing at Highland Park, in the county of Delaware, State of Pennsylvania, have invented new and useful Suspenders, of which the following is a specification.

My invention relates to improvement in suspenders. The invention relates especially to long stretch suspenders in which the elastic webbing extends the entire length of the suspenders; the two strands being secured together at the cross-over at the back. The objection to this construction, as heretofore practiced, has been the tendency of the stitching of the cross-over portion to rip, due to the fact that the stretch of the webbing is greater than the stretch of the stitching. The purpose of this invention is to overcome the said objection by inserting, between the strands or straps of elastic webbing at the cross-over, a reinforcing lining or layer of flexible material, such for example as a non-elastic fabric. This fabric is engaged by the stitching that holds the two elastic bands together at the cross-over, and maintains the stability of the stitching. I have found such fabric as cellophane, which is flexible but not elastic, to make a satisfactory lining or reinforcement. By forming this layer or reinforcement of diamond shape, with its margins slightly within the margins of the crossing bands of elastic webbing, when inserted and stitched between the two crossing bands, the same forms an invisible reinforcement, which in no manner detracts from the appearance of the suspenders.

Referring to the drawings, which illustrate merely by way of example a suitable embodiment of my invention—

Fig. 1 is a front elevation of a pair of suspenders embodying my invention.

Fig. 2 is a fragmentary view of the cross-over portion, on an enlarged scale.

Fig. 3 is a similar view with part broken away to show the reinforcement layer.

Similar numerals refer to similar parts throughout the several views.

In Fig. 1, I show the complete pair of suspenders with the two strands or shoulder straps 4 and 5 of elastic webbing, each

extending from a cast-off 6, which secures the button hole attachment 7, at one end, to the button hole tab 8 at the other end. 55 The two bands or straps 4 and 5 cross at 9, and are stitched together at their crossing margins, preferably with the two rows of stitching, close to and parallel with the margins of the overlapping bands, as at 10, but with the reinforcing piece 11, as shown in Fig. 3, first interposed and having such extension, as to receive said rows of stitches.

The essential feature or characteristic of 65 this invention is that the reinforcing strip or layer 11, of comparatively stiff or stable material, forms a relatively firm body to and through which the stitching is secured, and to which the overlying bands of elastic webbing are attached by said stitching. With such arrangement, any pull or stress, by the webbing against the stitching, is resisted chiefly by the reinforcing strip 11. 70 Where the crossed or overlapping bands of 75 webbing are stitched directly together, without reinforcement, some of the stitches may engage the rubber strands in the webbing, and these will tend to break away under stress, and also because of deterioration 80 in the rubber. This makes the connection between the crossing straps insecure, and distortion will result. By means of the reinforcement herein described distortion is 85 prevented, and the cross-over sections are held smooth and flat and firmly secured together, despite the uneven strains to which either of the two bands 4 and 5 may be subjected.

What I claim is:—

In suspenders, the combination of two shoulder straps of continuous elastic webbing, crossing at the back, and a reinforcing layer of non-elastic material interposed 95 between said straps, having an area and shape corresponding substantially with the area of the crossing portions of the elastic webbing and having its margins within the margins of said webbing, said crossing portions of the webbing and said reinforcing layer stitched together on lines adjacent their respective margins. 100

FREDERICK C. SIMMONS.
